UNITED STATES PATENT OFFICE.

SAMUEL S. ROBERTS, OF PITTSBURGH, PENNSYLVANIA.

SAFETY TOOL-RETAINER.

1,142,983.

Specification of Letters Patent. Patented June 15, 1915.

Application filed June 3, 1914. Serial No. 842,716.

To all whom it may concern:

Be it known that I, SAMUEL S. ROBERTS, a citizen of the United States, residing at Pittsburgh, in the county of Allegheny and State of Pennsylvania, have invented a new and useful Safety Tool-Retainer, of which the following is a specification.

My invention relates to the construction of pneumatic hammers, pneumatic drills, and similar pneumatic tools having cutters, drills, rivet snaps, etc., removably secured thereon or thereto, and the invention more particularly relates to the construction of means for maintaining such tools in position in the tool socket during the operation of the hammer or drill.

One object of my invention is to provide a safety tool retainer having novel means whereby the tool shank is engaged and movably secured in retaining the tool in place in the socket of pneumatic hammers, drills and like tools which employ gaseous fluid pressure, such as air and steam, as the motive fluid.

Another object of my invention is to provide a tool retainer having novel means for fastening the tool shank which enables the quick replacement and removal of the tools.

Still further objects of the invention will become apparent as the invention is more fully described hereinafter and pointed out in the appended claim.

Referring to the drawings forming part of this specification, Figure 1 is a plan of a pneumatic hammer, partly in section, the section being taken on the line I—I of Fig. 5, having a tool retainer constructed and arranged and applied for use thereon in accordance with my invention. Fig. 2 is a detail plan of one-half of the sectional bushing employed in securing the tool in the tool socket of the hammer. Fig. 3 is a sectional plan of the tool end of the pneumatic hammer, the section being taken on the line III—III of Fig. 4. Fig. 4 is a transverse section, taken on the line IV—IV of Fig. 3, showing the end of the hammer cylinder. Fig. 5 is a similar transverse section, the section being taken on the line V—V of Fig. 3, showing the end of the tool retaining bushing.

In the accompanying drawings, in which my invention is shown as applied to a pneumatic hammer, the numeral 2 designates the hammer cylinder or barrel having a lengthwise extending bore 3 containing the re-

ciprocatory piston 4. The cylinder is provided on one end with a handle 5 of the usual construction and the other end is provided with a counterbore or recess forming 60 a socket 6. The socket 6 has a counterbore of larger diameter to receive the two sections of the split bushing 7 forming part of the tool retaining mechanism.

The valve mechanism and the valve operating mechanism in the handle of the hammer may be of any of the various well known constructions, and not forming part of my invention, are not shown or described.

Mounted in the socket 6 of the hammer to 70 move lengthwise therein is a rivet snap 10 having a shank 11 with a collar 12 on its inner end of a larger diameter and preferably formed integral therewith, the collar end of the shank 11 being arranged to be 75 operatively engaged by the piston 4 which reciprocates within the bore 3 of the cylinder 2 in the usual known manner. The face or outer end of the rivet snap 10 is provided with a cup-shaped recess 13 which in cross 80 section has the contour of the heads of the rivets formed with the hammer.

When a chisel or other cutting tool is used with the pneumatic hammer, or when my invention is applied for use in securing 85 drills on the reciprocating piston of a pneumatic or steam drill, the shank of such tools will be formed with the reduced portion 11 and enlargement or collar 12, in the manner shown, as will be readily understood. 90

Secured in the counterbore of the socket 6 is the sectional bushing 7 which is divided on its diametral center to make two symmetrical halves. The bushing 7 has a central opening 14 of a diameter the same or 95 very slightly larger than that of the shank 11 of the rivet snap or other tool. The flange 15 of the bushing 7 is made hexagonal or is squared to receive a wrench or other turning tool in applying the bushing in 100 place.

In the end of the hammer cylinder 2, at one side of the counterbore, is a small hole 16 which extends lengthwise parallel with the bore 3 of the cylinder, and which is 105 counterbored, its outer end being closed with a screw threaded plug 17. The plug is provided with an axially central opening and projecting through the hole is a pin 18 having a collar 19 at an intermediate 110 point in its length. A helical spring 20 is positioned within the counterbored portion

of the hole 16 with one end in engagement with the jog forming the bottom of the counterbore and the other engaging with the collar 19 on the pin 18 so as to normally hold the pin in extended position. The outer end of the pin 18 is arranged to project into a registering hole 21 in the flange 15 of one section of the split bushing 7, this hole being positioned to receive the pin 18

10 when the bushing 7 is in tool holding position in the end of the hammer cylinder 2.

The counterbore forming the socket 6, at an intermediate point in its length, is provided with an annular recess 22, and this 15 recess is connected by two slots or recesses 23, 23, (see Fig. 4) in the walls of the recess forming the socket, these recesses being arranged to extend lengthwise parallel with and on diametrically opposite sides of 20 the lengthwise center of the hammer cylinder 2.

The bushing 7 has shoulders 24, one being provided on each side of each section of the bushing, which are arranged to enter 25 the annular recess 22 in the wall of the counterbore or socket 6 through the parallel slots 23 extending from the end of the hammer into the annular recess 22, so that when the split bushing 7 is applied to the 30 hammer cylinder to hold the rivet snap 10 in place, by moving the bushing 7 a quarter turn the lugs 24 on the bushing sections become seated in the annular recess 22 so as to be in holding position, and by engagement 35 with the collar 12 on the end of the shank 11 of the tool, prevent unseating or removal of the tool from the hammer.

In constructing rivet snaps and other tools for use with my improved tool retainer, the shank 11 thereof is made of such 40 length that the collared end 12 thereof will engage with the jog or shoulder defining the bottom of the counterbored recess forming the socket 6 and will hold the face 25 on the 45 rivet snaps or other tool so that it does not at any time engage with the adjacent face of the bushing 7 in the operation of the hammer, this construction materially reducing liability of breakage of the tools in 50 service.

In assembling the parts, the two halves of the bushing 7 are placed in position on the shank 11 of the rivet snap or other tool and the bushing while encircling the shank 55 is then inserted in the recessed end or socket 6 of the hammer cylinder, the lugs 24 on the inner end of the bushing sections being positioned within the recess 22 opposite the inner ends of the parallel slots 23 which

are located in opposite sides of the socket 60 6. After the bushing 7 is placed in such position it is given a quarter turn which moves the lugs 24 out of a position registering with the inner end of the parallel recesses 23 into a position between these recesses. The spring pressed pin 18 in the 65 socket end of the hammer cylinder then moves outwardly to extend into the hole 21 in the bushing, and acts to prevent turning of the bushing 7 until it is desired to 70 remove the tool and bushing. When it is desired to remove the split bushing 7, in order to replace the rivet snap 10 with another, or with a different type of tool, a pin of suitable size is pushed into the hole 21 75 in the bushing 7 so as to depress the pin 18 in the socket end of the hammer until its outermost end is in line with the joint between the adjoining faces of the flange 15 on the bushing and the face of the end of 80 the hammer. When in this position the bushing 7 is readily turned until the lugs 24 register with the slots 23 and the bushing and tool are then removed endwise.

The advantages of my invention, which 85 will be apparent to those skilled in the art, arise from the simplicity of my improved tool retaining mechanism and the ease with which it is manipulated in putting the tools in place and in removing them. The apparatus is strong and durable and will not require frequent or expensive repairs or occasion delays in the operation of hammers of 90 which it forms a part.

Modifications in the construction and arrangement of the parts may be made without departing from my invention as defined in the appended claim.

I claim:

The combination with a hollow body having internal longitudinal slots extending from one end and terminating in an internal annular groove, of a tool holder including segmental portions forming a cylindrical body when assembled, each of said portions having a projection thereon adapted to move along one of the slots and be turned into the groove, and a tool having a shank embraced by the holder and provided with a lateral enlargement for engagement with the inner 100 end of the tool holder to prevent displacement of the tool.

In testimony whereof, I have hereunto set my hand.

SAMUEL S. ROBERTS.
